DISPOSABLE FILTER CANISTER FOR A BREATHING SYSTEM

Gale E. Dryden, Indianapolis, Ind., assignor to Dryden
Corporation, Indianapolis, Ind.

Filed May 28, 1971, Ser. No. 148,271

Term of patent 14 years

Int. Cl. D24—01

U.S. Cl. D83—1 G

Fig. 1.

Fig. 2.

Fig.3.

Fig.4.

FIG. 1 is a perspective view taken from the front, top and right side of a disposable filter canister for a breathing system, showing my new design.

FIG. 2 is another perspective view taken from the rear, bottom and left side thereof.

FIG. 3 is a perspective view taken from the front, top and right side of a modified form of the disposable filter canister for a breathing system, as shown in FIG. 1.

FIG. 4 is another perspective view taken from the rear, bottom and left side of FIG. 3.

I claim:

The ornamental design for a disposable filter canister for a breathing system, as shown and described.
